[57] CLAIM

The ornamental design for a golf club head, as shown and described.

DESCRIPTION

FIG. 1 is a perspective view of a golf club head showing my new design. The broken line showing of a shaft portion is for illustrative purposes only.

FIG. 2 is a top plan view thereof.

FIG. 3 is a rear elevational view thereof.

FIG. 4 is a bottom view thereof.

FIG. 5 is a front elevational view thereof.

FIG. 6 is an end elevational view thereof.

FIG. 7 is an end elevational view taken from the opposite side of FIG. 6.

The characteristic feature of my new design resides in the particular configuration of the undercut wall of the cavity in combination with the particular club head form shown.

FIG. 1.

FIG. 2.

FIG. 3.

FIG. 6.

FIG. 4.

FIG. 7.

FIG. 5.
